UNITED STATES PATENT OFFICE.

ANTON VAN VEEN, OF WEST HARTFORD CONNECTICUT, ASSIGNOR TO THE FULLER BRUSH COMPANY, OF HARTFORD, CONNECTICUT, A CORPORATION OF CONNECTICUT.

WIRE-TWISTING MACHINE.

Application filed January 30, 1925. Serial No. 5,731.

This invention relates to the class of wire twisting machines more especially designed for use in the manufacture of brushes in securing bristles or other material to a wire structure by a twisting operation, and an object of the invention, among others, is the production of a machine of this class that shall be simple in construction and particularly efficient in operation.

10 One form of machine embodying the invention and in the construction and use of which the objects herein set out, as well as others, may be attained, is illustrated in the accompanying drawings, in which—

15 Figure 1 is a top view of my improved machine, with parts broken away to show construction.

Figure 2 is a view in front elevation of the machine.

20 Figure 3 is a top view, scale enlarged, of that end of the machine bearing the tail stock.

Figure 4 is a view in rear elevation of this end of the machine.

25 Figure 5 is a view in section on a plane denoted by the dotted line 5—5 of Figure 1, scale enlarged, the tail stock, however, being at the forward limit of its movement.

Figure 6 is a similar view on a plane denoted by the dotted line 6—6 of Figure 1.

30 Figures 7, 8 and 9 are top views of the machine with parts broken away to show construction, and illustrating different steps in the twisting of the wire.

35 In the operation of twisting wires to secure brush material thereto it is necessary, as is known by those skilled in the art, to twist the ends separately from that part within which said material is secured, such part containing the brush material usually being twisted first and the ends being then twisted. The improved machine illustrated and described herein embodies means for effecting these results in a rapid and efficient manner, in the accompanying drawings the numerals 10 indicating the bed of the machine, that may be mounted upon any suitable supports, as legs 11, and which machine has standards 13—14 for bearings of a driving spindle 15 having motion imparted to it,

as by means of a clutch, one member 16 of which may be driven as by means of a belt (not shown) passing around such member. This spindle is provided with a chuck 17 for holding the wires to be twisted, which chuck may be operated as by means of a chuck actuating lever 18 in any ordinary and well known manner. The clutch may be operated as by means of a clutch actuating lever 19, all in a manner that will be readily understood. As the parts just referred to, do not, except in connection with other parts to be more specifically set forth, embody the present invention, a further and detailed description is omitted herein, it being mentioned, however, that the chuck 17 includes chuck jaws 20 as a part thereof.

A tail stock is mounted on the opposite end of the bed from the parts just described, such tail stock comprising a base 21 slidably mounted on the bed and moved to the backward limit of its play as by means of a weight 22. A chuck support 23 is secured to the base, and chuck mechanism is mounted on said support, said mechanism comprising two pairs of jaws each pair of which includes a stationary jaw 24 or 25 and a movable jaw 26 or 27, as shown in dotted lines in Figure 3 of the drawings. These movable jaws are preferably spring pressed for movement away from the stationary jaws, as by means of a spring 28. Jaw actuating levers 29—30 are employed to close the jaws and to release them for opening movement, the lever 29 having a handle 31 for manual operation and the lever 30 being operatively connected with the lever 29, as by means of a link 32 whereby the two pairs of chuck jaws are operated simultaneously, one set being opened when the other set is being closed,

80 the ends of the levers 29—30 being preferably formed to cam shape, as shown in Figure 3, to accomplish this result, in which figure the pair of jaws at the left are in their open position, and those at the right are closed, the handle 31 being swung to the right to reverse the position of said jaws.

In the operation of twisting the brush material two wires 33 are commonly employed, the brush material 34 being evenly distrib-

uted in a layer between such wires, and the latter are caused to be grasped by the chuck jaws at certain points, and as shown in Figure 1 of the drawings, in which the inner 5 ends of the jaws at the right and the pair of jaws nearest the lengthwise center of the machine, and at the left thereof, are shown as grasping the wires. The machine being now operated to twist the wires, as shown in 10 Figure 7, such wires are consequently shortened, and the mechanism comprised in this invention is constructed to permit this shortening of the wires and to permit the chuck jaws to be opened without changing their 15 position with respect to the wires, and by a single movement of the chuck actuating levers.

This mechanism comprises a stop 35 secured to the bed 10 and adapted to temporarily locate the base 21 in an advanced position and thereby temporarily prevent its backward movement to the position shown in Figures 1 and 3 of the drawings, in this advanced position the back edge of said base 25 resting against said stop that also operates in connection with a striker 36 secured to a controller 37 pivotally attached to a block 38 secured to the base 21, and as shown in Figures 3 and 6 of the drawings. In the 30 preferred form of construction the striker is provided with means of adjustment lengthwise thereof as by a threaded attachment, and as shown in Figures 3 and 4 of the drawings. The controller has a holding 35 and releasing latch pivotally secured thereto at its outer end, the nose 39 of such latch being adapted to make contact with a releasing plate 41 secured to the edge of the bed 10, and an edge of said nose also being adapted 40 to make contact with a resetting plate 42 also secured to the edge of the bed 10, and as shown in Figure 4 of the drawings. A retainer 43 is secured to and projects upwardly from the base 21, in position to receive the heel 40 of the holding and releasing 45 latch, which heel is adapted to project across and rest upon the upper end of said retainer to hold said latch in its uppermost or raised position, and as shown in Figures 5 and 9 50 of the drawings.

In the operation of the device, the parts being in the position shown in Figure 1, with the gripping jaws holding the wires 33 at points adjacent to the material 34, the 55 spindle 15 is set in motion and the twisting of the wires takes place. As this twisting progresses the wires are shortened, causing the base 21 to be moved toward the lengthwise center of the machine, during which 60 movement the striker passes along the top of the stop 35 until the parts reach the position shown in Figure 7 of the drawings, when the machine is stopped at the completion 65 of the first stage of the twisting operation. In this position of the parts the

striker 36 has been drawn to a point a slight distance beyond the stop 35 and the ends of the twisted wires at the right hand end of the twisted structure project beyond the right hand end of the chuck jaws in the 70 chuck 17 and into a socket or stop piece 44 at the end of the spindle 15, and as shown in Figure 1 of the drawings, in which position such wires were placed when the brush structure was first clamped in position, the wires at the opposite end of the structure being originally placed in their proper positions.

The chuck at either end of the machine is now operated to release the wires, or both 75 chucks may be so operated, and the pull of the weight 22 will seat the striker 36 squarely against the stop 35, and as shown in Figure 3 of the drawings. The chucks are now operated to grip the wires near their opposite ends, the lever 29 being swung from the position shown in Figure 7 to the position shown in Figure 8, thus releasing the wires from the grip of the jaws 25-27 and causing them to be gripped by the jaws 24-26, and as shown in said Figure 8. The spindle 15 is now again put in operation and the extreme ends of the wires are twisted, during which operation the structure is again shortened, drawing the base 21 to the 90 position shown in Figure 9, in which position the striker 36 is separated a considerable distance from the stop 35. In this movement of the base 21 the nose 39 of the holding and releasing latch has engaged with the edge of the releasing plate 41 that acts to raise this end of the controller 37 until the heel 40 of said latch is above the upper 95 end of the retainer 43, when, said latch being sprung actuated in one direction, as by a spring 48, its heel 40 is swung over the upper edge of the retainer and the controller 37 is thereby held in its raised position, the striker 36 in this position being higher than the top edge of the stop 35.

The chuck jaws being now released for removal of the twisted structure the weight 22 draws the base 21 to its rearwardmost position, and as shown in Figure 1 of the drawings, in this movement the striker 36 passing over the stop 35. As the base 21 reaches the limit of its backward movement the nose 39 of the holding and releasing latch strikes the resetting plate 42, swinging said latch on its pivot to the position shown in Figure 1, 100 thereby permitting the controller 37 to fall, as by gravity, and lower the striker 36 into contact with the stop 35 and also lower the latch behind the retainer 43, the latter now operating to hold the latch in this position, 105 the parts being now in position for another 110 twisting operation.

In accordance with the provisions of the patent statutes I have described the principles of operation of my invention, together 115

with the machine which I now consider to represent the best embodiment thereof; but I desire to have it understood that the machine shown is only illustrative, and that the invention may be carried out by other means and applied to uses other than those above set out.

I claim—

1. A wire twisting machine including a movable support, wire twisting mechanism including means on said support for gripping wires to be twisted, means for releasing said gripping means, means for thereafter retaining said support in an advanced position after its forward movement caused by the twisting of said wires, and means for releasing said retaining means to permit said support to return to its initial position.
2. A wire twisting machine including a movable support, wire twisting mechanism including means on said support for gripping wires to be twisted, means for retaining said support in an advanced position after its forward movement caused by the twisting of said wires, and means operated by the movement of said support to release said retainer to permit said support to return to its initial position.
3. A wire twisting machine including a movable support, wire twisting mechanism including means on said support for gripping at different points the wires to be twisted, means for retaining said support in an advanced position after its forward movement caused by the twisting of said wires and during the release of said gripping means, and means for releasing said retaining means to permit said support to return to its initial position.
4. A wire twisting machine including a movable support, wire twisting mechanism including means on said support for gripping wires to be twisted, means for retaining said support in an advanced position after its forward movement caused by the twisting of said wires, and means operated by the movement of said support to position said retaining means to permit said support to return to its initial position and to reposition said retaining means for a repeated operation.
5. A wire twisting machine including a movable support, wire twisting mechanism including means on said support for gripping wires to be twisted, a stop, a member movably mounted on said support to engage said stop and retain said support in an advance position after its forward movement caused by the twisting of said wires, and means for releasing said retaining means to permit said support to return to its initial position.
6. A wire twisting machine including a movable support, wire twisting mechanism

including means on said support for gripping wires to be twisted, a stop, a member pivotally mounted on said support to engage said stop and retain said support in an advance position after its forward movement caused by the twisting of said wires, and means for releasing said retaining means to permit said support to return to its initial position.

7. A wire twisting machine including a movably mounted support, wire twisting mechanism including means on said support for gripping wires to be twisted, a stop, a member movably mounted on said support to engage said stop and retain said support in an advance position after its forward movement caused by the twisting of said wires, means on said member to hold it in a predetermined position, and means for releasing said holding means.

8. A wire twisting machine including a movably mounted support, wire twisting mechanism including means on said support for gripping wires to be twisted, a stop, a controller member movably mounted on said support to engage said stop and retain said support in an advance position after its forward movement caused by the twisting of said wires, a setting latch member on said controller member, and means against which one of said members is moved to effect the setting of said latch member.

9. A wire twisting machine including a movably mounted support, wire twisting mechanism including means on said support for gripping wires to be twisted, a stop, a controller member movably mounted on said support to engage said stop and retain said support in an advance position after its forward movement caused by the twisting of said wires, a setting latch member movably mounted on said controller member, means to receive said latch member to hold said controller member in its retaining position, and means against which said controller member is moved to operate it to permit said latch member to act.

10. A wire twisting machine including a movably mounted support, wire twisting mechanism including means on said support for gripping wires to be twisted, a stop, a controller member movably mounted on said support to engage said stop and retain said support in an advance position after its forward movement caused by the twisting of said wires, a setting latch member movably mounted on said controller member, means to receive said latch member to hold said controller member in said position, and means against which said latch member is moved to raise said controller member and permit said latch member to act to hold said controller member in a raised position.

11. A wire twisting machine including a movably mounted support, wire twisting

- mechanism including means on said support for gripping wires to be twisted, a stop, a controller member movably mounted on said support to engage said stop and retain said support in an advance position after its forward movement caused by the twisting of said wires, a setting latch member on said controller member, means for returning the setting latch member to its normal position on said controller member, and means against which one of said members is moved to permit said latch member to act.
12. A wire twisting machine including a movably mounted support, wire twisting mechanism including means on said support for gripping wires to be twisted, a stop, a controller member movably mounted on said support to engage said stop and retain said support in an advance position after its forward movement caused by the twisting of said wires, a setting latch member movably mounted on said controller member, means located in the parts of one of said members to move said controller member to permit said latch member to act, and means against which said latch member is pressed to move it to release said controller member.
13. A wire twisting machine including a movably mounted support, wire twisting mechanism including means on said support for gripping wires to be twisted, a stop, a member to engage said stop and retain said support in an advance position after its forward movement caused by the twisting of said wires, and means for retaining said member in a position to permit said support to return to its normal position of rest.
14. A wire twisting machine including a movably mounted support, wire twisting mechanism including means on said support for gripping wires to be twisted, a stop, a member movably mounted on said support to engage said stop and retain said support in an advance position after its forward movement caused by the twisting of said wires, a latch upon said member, a retainer to receive said latch to hold said member in one position, and means to operate said latch to disengage it from said retainer.
15. A wire twisting machine including a movable support, wire twisting mechanism including means on said support for gripping wires to be twisted, means for releasing said gripping means, means operated by the movement of said support to retain the latter in an advanced position after its forward movement caused by the twisting of said wires, and means for operating said retaining means to permit said support to return to its initial position.
16. A wire twisting machine including a movable support, wire twisting mechanism including means on said support for gripping wires to be twisted, means operated by the movement of said support for retaining the latter in an advanced position after its forward movement caused by the twisting of said wires, means operated by the movement of the support to position said retaining means to permit said support to return to its initial position, and means operated by the movement of said support to reposition said retaining means for a repeated operation.
17. A wire twisting machine including a movable support, wire twisting mechanism including means on said support for gripping wires to be twisted, a stop, and a member movably mounted on said support to engage said stop and retain said support in an advanced position after its forward movement caused by the twisting of said wires and to release said support to permit it to return to its initial position.
18. A wire twisting machine including wire gripping mechanism movable in one direction by the twisting of the wires, means for moving the mechanism in the opposite direction, and means for controlling the extent of operation of said last mentioned means so as to cause the mechanism to be moved thereby into more than one predetermined position.
19. A wire twisting machine including wire gripping mechanism movable in one direction by the twisting of the wires, means for moving the mechanism in the opposite direction, and means for controlling the extent of operation of said last mentioned means so as to cause the mechanism to be moved thereby into more than one predetermined position, said control means including an adjustable member for selectively varying one of said predetermined positions.
20. A wire twisting machine including wire gripping mechanism movable in one direction by the twisting of the wires, means for moving the mechanism in the opposite direction, and means for controlling the extent of operation of said last mentioned means so as to cause the mechanism to be moved thereby into more than one predetermined position, said control means including elements arranged to cooperate during the movement of the mechanism by the twisting of the wires to cause the mechanism to be moved into one of said predetermined positions.
21. A wire twisting machine including wire gripping mechanism movable in one direction by the twisting of the wires, means for moving the mechanism in the opposite direction, and means for controlling the extent of operation of said last mentioned means so as to cause the mechanism to be moved thereby into more than one predetermined position, said control means including elements arranged to be automatically actuated during the movement of the mechanism in opposite directions.

22. A wire twisting machine including mechanism for successively gripping at different points the wires to be twisted, which mechanism is movable in one direction by the twisting of the wires, means effective to move the mechanism in the opposite direction, and means for controlling the extent of operation of said last mentioned means so as to cause the mechanism to be moved thereby into one position for gripping the wires at one point and into another position for gripping the wires at a different point.

ANTON VAN VEEN.
